US0D1016002S

(12) **United States Design Patent** (10) **Patent No.:** **US D1,016,002 S**
(45) **Date of Patent:** **** Feb. 27, 2024**

(54) **BATTERY**

(71) Applicant: **Koki Holdings Co., Ltd.**, Tokyo (JP)

(72) Inventors: **Yoshiki Aoki**, Ibaraki (JP); **Shuji Takeda**, Ibaraki (JP); **Shota Kanno**, Ibaraki (JP)

(73) Assignee: **Koki Holdings Co., Ltd.**, Tokyo (JP)

(**) Term: **15 Years**

(21) Appl. No.: **29/850,842**

(22) Filed: **Aug. 23, 2022**

(30) **Foreign Application Priority Data**

Mar. 25, 2022 (JP) ..... 2022-006239 D

(51) **LOC (14) Cl.** **13-02**

(52) **U.S. Cl.**

USPC **D13/103**

(58) **Field of Classification Search**

USPC D3/103, 107, 108, 110, 112, 118, 119, D3/122, 184, 199

(57) **CLAIM**

The ornamental design for a battery, as shown and described.

DESCRIPTION

FIG. 1 is a perspective view of a battery showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the battery that form no part of the claimed design.

1 Claim, 8 Drawing Sheets
